UNITED STATES PATENT OFFICE

WILLIAM R. KREBS, OF BALTIMORE, MARYLAND

FOLDABLE PAPER BOX

Application filed April 3, 1931. Serial No. 527,469.

This invention relates to folding boxes and has special reference to a folding paper box.

One important object of the invention is to provide an improved single piece blank from which a complete box and cover can be folded.

A second important object of the invention is to provide an improved box folded from such a blank, the blank being so arranged as to permit a portion of the blank to be folded in one position as a cover and in a second position as a display flap.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a perspective view of the box open and ready for closing.

Figure 2 is a view in reduced scale of the blank from which the box is folded.

Figure 3 is a vertical section through the closed box from front to rear.

Figure 4 is a perspective view of the box arranged in display position.

Figure 5 is a rear view of the box arranged as in Figure 4.

Figure 6 is a longitudinal vertical section through the closed box looking towards the front.

In forming this box a suitable sheet of paper like material such as mill board, straw board or the like is cut and scored to produce a blank having a rectangular bottom portion 10. At each end of this bottom is a rectangular end flap 11 defined from the body 10 by a crease or score line 12. These flaps extend the full width of the bottom 10. Similarly a front flap 13 and rear flap 14 are defined from the bottom 10 by the fold lines 15. These flaps 13 and 14 extend the full length of the

bottom and the flaps 11, 13, and 14 are all of the same width. In the corners between the end flaps 11 and front flap 13 are square corner flaps 16 defined from the flaps 11 and 13 by scored fold lines 17 and each having a diagonal fold line 18 scored therein. Tabs 19

50 of the same longitudinal dimensions as the flaps to which they are attached extend from the free edges of the flaps 11 and 13 and are defined therefrom by scored fold lines 20. A

cover portion 21 extends from the free edge 55 of the rear flap 14 and is defined therefrom by a scored fold line 22. This cover is of substantially the same size as the bottom and is divided into equal forward and rear portions by central scored fold lines 23 extending inwardly from the end edges of the cover and having their inner ends connected by a semi-circular slit 24 forming a tab 25. Carried by

the front edge of the cover is a front cover flap 60 26 defined from the cover by a fold line 27. A rear flap portion 28 extends from the rear edge of each end flap 11 and is defined therefrom by a scored fold line 29. These rear flaps are separated from the rear flaps 14 and

70 cover 21 by slits 30. Locking slits 31 are used so that these flaps 28 may be detachably connected in setting up the box.

The box is formed by folding the front and end flaps vertically upwards with respect to 75 the bottom 10, the corner flaps 16 being doubled on the fold lines 18 to permit this. The rear flaps 28 then are folded toward each other and interlocked. The tabs 19 are folded inwardly. Finally the back flap 14 is folded vertically upward, the cover folded forward and the front cover flap bent down and inserted in the box.

Should it be desired to use the box cover 85 as a display device the auxiliary rear flaps are disconnected and brought together behind the main rear flap 14 and the cover doubled on its central fold lines to cause the tab 25 to project upwardly, the front cover 90

flap being brought into position against the front face of the main rear flap 14.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. A blank for folding boxes consisting of a single sheet of material cut and scored to provide a rectangular bottom portion, end, front and main rear flaps extending from the respective edges of the bottom and defined therefrom by fold lines, square corner portions in the corners between the end and front flaps and defined therefrom by fold lines, tabs on the free edges of the front and end flaps, a cover portion extending from the free edge of the rear flap and defined therefrom by a fold line and having a front cover flap extending from the free edge of the cover and defined therefrom by a fold line, said cover being divided into forward and rear portions by fold lines extending inwardly from the end edges of the cover and having their inner ends connected by a semi-circular slit, and auxiliary rear flaps extending from the rear edges of the end flaps and defined therefrom by fold lines, said auxiliary end flaps being separated from the main end flap and cover by slits and having cooperating locking slits adjacent their rear ends.

2. A box formed from a blank consisting of a single sheet of material cut and scored to provide a rectangular bottom portion, end, front and main rear flaps extending from the respective edges of the bottom and defined therefrom by fold lines, square corner portions in the corners between the end and front flaps and defined therefrom by fold lines, tabs on the free edges of the front and end flaps, a cover portion extending from the free edge of the main rear flap and defined therefrom by a fold line and having a front cover flap extending from the free edge of the cover and defined therefrom by a fold line, said cover being divided into forward and rear portions by fold lines extending inwardly from the end edges of the cover and having their inner ends connected by a semi-circular slit, and auxiliary rear flaps extending from the rear edges of the end flaps and defined therefrom by fold lines, said auxiliary end flaps being separated from the main end flaps and cover by slits and having cooperating locking slits adjacent their rear ends, the front, main rear and end flaps be-

ing folded up from the bottom with the corner flaps folded inwardly, said cover being selectively folded to cover the box and to be doubled and project up at the rear of the box with the tab defined by the semi-circular cut projecting upwardly, said auxiliary rear flaps being folded to overlap and connect at their ends selectively in front of and at the rear of the main rear flap accordingly as the cover is in box closing and display positions.

In testimony whereof I affix my signature.

WILLIAM R. KREBS.
